(No Model.)

C. G. EVANS.

PISTON.

No. 591,392.

Patented Oct. 12, 1897.

WITNESSES:

Dear Mr. Titchell
Rev. G. Foster, Jr.

BY

INVENTOR
C. G. Evans.

ATTORNEYS.

UNITED STATES PATENT OFFICE.

CHARLES G. EVANS, OF UNION, CANADA.

PISTON.

SPECIFICATION forming part of Letters Patent No. 591,392, dated October 12, 1897.

Application filed December 14, 1896. Serial No. 615,556. (No model.)

To all whom it may concern:

Be it known that I, CHARLES G. EVANS, of Union, in the Province of British Columbia and Dominion of Canada, have invented a new and Improved Piston, of which the following is a full, clear, and exact description.

The object of the invention is to provide a new and improved piston for steam-engines arranged to prevent all leakage of steam past the piston-packing and without undue friction of the packing-rings on the cylinder-wall.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a longitudinal section of the improvement. Fig. 2 is a transverse section of the same on the line 2 2 of Fig. 1, and Fig. 3 is a plan view of the ends of one of the packing-rings.

The improved piston is provided with a piston-body A, secured on a piston-rod B, connected in the usual manner with the driving-shaft of the engine, the piston being reciprocated in the cylinder C by the pressure of the steam or other motive agent alternately acting on the ends of the said piston.

On the front face of the piston-body A is arranged a follower D, fitted to slide longitudinally on the piston B and rigidly connected by rods or pins E with a follower D', held on the other face of the body A, the said rods or pins being fitted to slide in suitable bearings in the body A. The follower D is connected by a series of longitudinally-extending rods

F with a ring G, fitted to slide longitudinally in a recess A', formed in the body A, and the other follower D' is similarly connected by rods F' with a ring G', fitted to slide in a recess A'', likewise formed in the body A. The rings G and G' are formed on their peripheries with bevels engaging corresponding bevels on the inside of the packing-rings H and H', extending through the recesses A' and A'' to engage the inside of the cylinder C and form a packing for the piston.

The packing-ring H is arranged near the face of the piston having the follower D', and the other packing-ring H' is arranged near the face having the follower D, as is plainly

shown in the drawings, so that when the steam enters the right-hand end of the cylinder C and presses against the follower D then the latter moves to the left and, in doing so causes a sliding of the other follower in the same direction and a sliding of the rings G and G' in the same direction to cause an expansion of the packing-ring H and a releasing of the packing-ring H'.

When the steam enters the left-hand end of the cylinder C, it presses on the follower D', and the latter is caused to slide to the right, carrying the follower D and the rings G G' in the same direction, whereby the packing-ring H' is expanded and the previously-expanded packing-ring H is released. Thus that side of the piston containing the exhaust-steam is packed by the corresponding packing-ring, while the ring on that side of the piston containing the live steam is in a release position. It will be seen that by the arrangement described the followers D and D', as well as the expanding and releasing rings G and G', move in unison in longitudinal directions, the followers on one side of the piston directly actuating the expansion and releasing ring for the opposite side of the piston.

In order to limit the inward sliding motion of the followers D and D', I provide the inner faces of the followers D and D' with beveled offsets D² D³, respectively, engaging the inner bevels of rings I I', respectively, held in annular recesses A³ A⁴, respectively, formed in the body A. Guard-rings J J', secured on the piston-body, extend a short distance over the faces of the rings I I', so as to hold the same in their recesses against longitudinal movement.

The rings H H' I I' are made in the form of split rings, so as to permit of expanding the rings and allowing the same to contract by their own resiliency, the rings H H' being expanded by the movement of the rings G G', respectively, and the rings I I' being expanded by the beveled offsets D² D³, respectively, on the followers D and D'. As shown in Fig. 3, each of the rings H H' is formed at its split end with a dovetailed tongue H², engaging a dovetailed recessed end H³ for securely connecting the ends with each other and still permit of expansion and contraction thereof for the purpose above described. The ends of the rings I I' are similarly constructed.

Each of the pins E is rigidly secured at one

end to the follower D, and the other end is formed with a conical offset E', engaging a corresponding aperture in the follower D'. The extreme outer end of the pin is formed 15 with a right-hand screw-thread E² and a left-hand screw-thread E³, of which the former is engaged by a nut K and the latter by a nut K', both having registering recesses K² K³ countersunk at their adjacent ends and adapted to be filled with Babbitt metal or other 20 material, which when cooled and set forms a locking-pin for securing the two nuts in position. A similar fastening is arranged for the pins or rods F F', which are secured at 25 one end in the rings G G' and at their other end by nut-locks, as described for the followers D D'.

The expanding and releasing rings G G' are 30 preferably made in sections, of which the top section is made of very hard steel, the lower section of ordinary steel, and the side sections of soft iron, so that they wear readily and produce an oval ring-wedge which sets the packing-rings H H' properly in a worn horizontal 35 cylinder oval in cross-section. It is understood that the rings I I' wear on their inner faces about in proportion to the wear of the packing-rings H H', so that an automatic adjustment always takes place as the offsets D² 40 D³ move farther inward on the rings I I', and consequently an expansion of the rings H H' in a corresponding degree takes place, so as to insure at all times a perfect packing of the piston in the cylinder. The faces of the body 45 A are recessed at A⁵ and A⁶ to permit the inner ends of the offsets D² and D³ to move the desired distance when the followers are pressed inward by the motive agent.

By the arrangement described it is evident 50 that the followers D D' are pressed inward such a distance as the expansion of the rings I I' allows, and consequently the rings H and H' do not expand against the inner surface of the cylinder C according to the force or pressure of the steam, but only according to the 55 amount of movement allowed by the said rings I and I', so that the rings are uniformly expanded with the inner wall of the cylinder C irrespective of the pressure of the motive agent in the ends of the cylinder as long as the pressure is sufficient for shifting the followers, as above described. The rings I I', encircling the followers, give sufficient resistance to the followers to prevent the same from 60 striking hard against their resting-surfaces when adjustment takes place.

Having thus fully described my invention, I claim as new and desire to secure by Letters Patent—

60 1. A piston, provided with packing-rings, and followers rigidly connected with each other and fitted to slide longitudinally by the pressure of the motive agent in the ends of the cylinder, the follower on one side of the 65 piston being connected with the packing-ring for the other side of the piston, substantially as shown and described.

2. A piston, provided with packing-rings, followers rigidly connected with each other and fitted to slide longitudinally by the pressure of the motive agent in the ends of the cylinder, the follower on one side of the piston being connected with the packing-ring for the other side of the piston, and a device for limiting the sliding motion of the followers and the expansion of the rings, substantially as shown and described. 70 75

3. A piston, provided with packing-rings, a device for expanding and releasing each of the said packing-rings, and followers rigidly connected with each other and fitted to slide longitudinally, the follower on one side of the piston being rigidly connected with the expansion and releasing device on the other side of the piston, substantially as shown and described. 80 85

4. A piston, provided with packing-rings, a device for expanding and releasing each of the said packing-rings, followers rigidly connected with each other and fitted to slide longitudinally, the follower on one side of the piston being rigidly connected with the expansion and releasing device on the other side of the piston, and a limiting device for each follower, for limiting the sliding motion of the same, substantially as shown and described. 90 95

5. A nut-lock, comprising a rod having right and left hand threads, and nuts on the said threads and formed with registering apertures adapted to be filled with a setting or hardening substance, the said apertures being countersunk at their adjacent ends, substantially as shown and described. 100

6. A piston, provided with an expansion-ring for the packing-ring, and made in sections of metal of different degrees of hardness, substantially as shown and described. 105

7. A piston having a body, a follower at each end of the body, two packing-rings running around the body, an expanding-ring beneath each packing-ring, and connections respectively between the followers and the expanding-rings farthest therefrom, substantially as described. 110 115

8. A piston having a body, a follower at each end of the body, expansive packing-rings, and connections respectively between the followers and the packing-rings farthest therefrom, whereby upon the movement of one follower the packing-ring farthest from said follower will be expanded, substantially as described. 120 125

9. A piston having a body, a follower thereon, an expansive packing-ring, an expanding-ring having connection with the packing-ring and moving to expand the same, and a connection between the follower and the expanding-ring, substantially as described.
